CLAIM

The ornamental design for a corner bench unit, as shown and described.

DESCRIPTION

FIG. 1 is a front perspective view of a corner bench unit according to the present invention wherein the corner bench unit does not include a shelf.

FIG. 2 is a front elevation view of the corner bench unit illustrated in FIG. 1.

FIG. 3 is a rear elevation view of the corner bench unit illustrated in FIG. 1.

FIG. 4 is a side elevation view of the corner bench unit illustrated in FIG. 1.

FIG. 5 is another side elevation view of the corner bench unit illustrated in FIG. 1.

FIG. 6 is a top plan view of the corner bench unit illustrated in FIG. 1; and,

FIG. 7 is a bottom plan view of the corner bench unit illustrated in FIG. 1.

The broken lines in FIGS. 1-7 depict slats on a bench portion of the corner bench unit and do not form a part of the claimed invention.
